UNITED STATES PATENT OFFICE.

CHARLES H. GATCHELL, OF BOSTON, MASSACHUSETTS.

ADJUSTABLE FIRE-POT.

No. 818,949.

Specification of Letters Patent.

Patented April 24, 1906.

Application filed April 6, 1905. Serial No. 254,208.

To all whom it may concern:

Be it known that I, CHARLES H. GATCHELL, a citizen of the United States, residing at Boston, in the county of Suffolk and State of Massachusetts, have invented certain new and useful Improvements in Adjustable Fire-Pots; and I do declare the following to be a full, clear, and exact description of the invention, such as will enable others skilled in the art to which it appertains to make and use the same.

This invention relates to improvements in adjustable partitions for stove and range fire-boxes.

15 The object of the invention is to provide a partition of this character by which the fire-box of a stove or range may be shortened, whereby only a portion of the same may be used, thus permitting a small fire to be made 20 in the box.

A further object is to provide means whereby that portion of the grate not being used for the fire may be closed, thus causing all the draft to pass through the portion of the grate 25 holding the fire, means being provided whereby the partition-plate may be increased in width to fit within fire-boxes that are wider than the main portion of the plate.

With these and other objects in view the 30 invention consists of certain novel features of construction, combination, and arrangement of parts, as will be hereinafter described and claimed.

In the accompanying drawings, Figure 1 is 35 a longitudinal vertical sectional view through the fire-box of a range, showing the application of the invention thereto. Fig. 2 is a detail perspective view of the device removed from the fire-box. Fig. 3 is a vertical sectional view through the same, taken on a 40 line with the adjusting mechanism of the supporting-plate. Fig. 4 is a side view showing the parts in folded position, and Figs. 5 and 6 are detail plan views of different forms of partition-plates.

Referring more particularly to the drawings, 1 denotes the partition-plate, on one side of which, near the lower edge, is formed a pair of laterally-projecting apertured ears 50 or lugs 2, which are adapted to engage an apertured lug 3, formed on the section 4 of an adjustable supporting-plate 5. The section 4 of the supporting-plate is slidably mounted on a lower section 6, said section 6 being provided on its edges with upwardly and inwardly 55 projecting flanges 7, which are adapted to en-

gage the opposite edges of the section 4, thereby holding the same in sliding engagement with the section 6.

On the outer side of the partition-plate 1 above the lug 2 is hingedly connected the upper end of a brace-bar 8, the lower end of which is bent at an angle and is provided with a T-shaped slot 9, adapted to engage a headed pin or stud 10, arranged on and projecting upwardly from the section 4 of the supporting-plate 5, whereby the partition-plate 1 is held in an upright position at right angles to the supporting-plate.

In order that the sections 4 and 6 of the plate 5 may be prevented from being entirely separated or slipped apart, one of the guide-flanges 7 is provided with an offset or projection 12, which is adapted to be engaged by a pin 13, projecting upwardly from the section 75 4, thus limiting the movement of the section 4 in one direction. In order to limit the movement of said section in the opposite direction, a pin or stud 14 is arranged adjacent to the outer edge of the section 6 to form a 80 stop against which the outer edge of the section 4 strikes when the plates are adjusted together.

In order to hold the sections 4 and 6 of the plate 5 in adjusted position, the upper section 85 4 is provided with a flat spring 15, on the free end of which is arranged a downwardly-projecting stud 16. This stud 16 is adapted to be forced by said spring through an aperture 17, formed in the plate-section 4, and 90 into engagement with one of a series of apertures 18, formed in the lower plate-section 6. The spring 15 is turned upwardly at its free 95 end to form a finger-piece 19, whereby the same may be lifted to disengage the stud 16 from the apertures 18, thus allowing the sections 4 and 6 to be adjusted to increase or decrease the length of the supporting-plate 5.

On one side of the partition-plate 1 adjacent to one edge of the same is arranged a supplemental plate 20, in which is formed horizontally-disposed slots 21, engaged by retaining-screws 22, secured in the partition-plate 1. By means of the slots 21 and screws 22 the supplemental plate 20 may be shifted to 105 increase the width of the partition-plate 1, thus enabling the same to be adjusted to the width of the fire-box in which it is arranged.

In arranging the partition within the fire-boxes the supporting-plate 5 is placed upon the grate at one end of the same, after which 110 the sections 4 and 6 thereof are slipped apart

to the desired degree to bring the partition-plate to the desired position in the fire-box 6, thus shortening or reducing the space in which the fire is to be made. This arrangement permits only a portion of the fire-box to be used and a small fire maintained therein.

In Figs. 5 and 6 are shown modified forms of the partition-plate 1, Fig. 5 showing the plate 1' as provided with vertically-disposed slots 23, while Fig. 6 shows a plate 1'' as formed with perforations or circular apertures 24. These constructions or forms of plates assist in the ventilation or draft of the fire.

15 In forming the partitions the partition-plate 1 will be constructed of considerably-heavier material than the supporting-plates, so as to resist the heat from the fire-box and to prevent the same from becoming warped 20 by the heat. In practice it is intended to form the partitions in standard sizes to correspond with the standard sizes of the fire-boxes of different ranges or stoves. The adjustable supplemental plate 20 on the partition-plate 1 is provided to enable the same to 25 be snugly fitted within odd sizes of fire-boxes.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of 35 this invention.

Having thus described my invention, what I claim as new, and desire to secure by Letters Patent, is—

40 1. An attachment of the class described,

comprising a base-plate composed of two overlapping sections, one of said sections being provided at its edges with flanges adapted to receive the other and to hold the sections in sliding engagement, and the lower section 45 being provided with a series of apertures, a spring-projected pin carried by the upper section and adapted to engage either of said apertures, a partition-plate hinged to said upper section, and a brace adapted to hold said partition-plate in an upright position.

2. An attachment of the character described, comprising a base-plate composed of upper and lower sections, guide-flanges formed on said lower sections to receive the upper 55 section, whereby the latter is held in sliding engagement with the lower section, a stop-pin arranged on said upper section to engage an offset on one of said guide-flanges to prevent the separation of said sections, a spring-projected stop-pin carried by said upper section to pass through a hole in said upper section, said lower section having a series of holes 60 therein, with one of which said spring-projected stop is adapted to engage, a partition-plate hingedly connected to said upper section, a hinged brace-bar to support said partition-plate in an upright position, and a supplemental plate adjustably connected to said partition-plate, whereby the width of the latter 65 may be increased, substantially as described.

In testimony whereof I have hereunto set my hand in presence of two subscribing witnesses.

CHARLES H. GATCHELL.
